(57) **CLAIM**

The ornamental design for a semiconductor wafer for mosaic solar cell fabrication, as shown and described.

DESCRIPTION

The present application is related to U.S. Patent application Ser. No. 29/765,295, now U.S. Pat. No. D945,956.

FIG. 1 is a top perspective view of a semiconductor wafer for a mosaic solar cell fabrication showing our new design; FIG. 2 is a top plan view of the semiconductor wafer for mosaic solar cell fabrication in an environment of use; FIG. 3 is a bottom plan view thereof;

FIG. 4 is a front elevation thereof;

FIG. 5 is a rear elevation view thereof;

FIG. 6 is left elevational view thereof; and,

FIG. 7 is a right elevation view thereof.

The broken line in FIG. 2 depicts environmental structure and forms no part of the claimed design.

The semiconductor wafer for mosaic solar cell fabrication is scribed to produce four mosaic solar cell elements.
